UNITED STATES PATENT OFFICE.

ELISHA S. STAPLES AND ROUSE H. ARNOLD, OF SENECA FALLS, NEW YORK.

ROCKING GRATE FOR FURNACES.

SPECIFICATION forming part of Letters Patent No. 440,286, dated November 11, 1890.

Application filed May 12, 1890. Serial No. 351,501. (No model.)

To all whom it may concern:

Be it known that we, ELISHA S. STAPLES and ROUSE H. ARNOLD, citizens of the United States, residing at Seneca Falls, in the county of Seneca and State of New York, have made certain new and useful Improvements in Rocking Grates for Furnaces, which improvements are fully set forth and described in the following specification, reference being had to the accompanying sheet of drawings, in which—

Figure 1 is a top view of the ash-pit section of a furnace or steam-generator; and Fig. 2, an enlarged sectional view of a portion of said ash-pit, having connected therewith portions 15 of the grate, fire-pot, and jacket of a steam-generator. Fig. 3 is a view of the under side of a portion of the fire-pot, showing one of our fixed (non-rocking) grate-sections secured thereto. Fig. 4 is an enlarged perspective 20 view of one of the series of journal-bearings provided to support the grate-bars.

Our invention has particular relation to rocking grates; and it consists in, first, a peculiar construction of journal-bearings to support the ends of the rocking sections of such 25 grates, and, second, lugs on the fire-pot to receive and support the front and rear fixed sections of said grate.

The rocking grate itself is of a form commonly used, and consists of a series of bars *m*, having their opposite sides or edges serrated, the serrations of adjacent edges being so planned that the teeth of one section enter the notches of the next adjoining section.

One of the grate-bars *m*, preferably the central one of the series, projects outward beyond the shell of the ash-pit and may be connected by any suitable system of levers by which said grate may be rocked. The several journaled grate-sections should be connected by a bar extending underneath said sections and connected therewith by pivot-joints in a manner common to this class of grates, said means of connection forming no part of our present 45 invention.

Referring now to the bearings that support the journals of the grate-bars, the letters *N* indicate boxes of, preferably, angular shape cast on the interior of one side of the ash-pit 50 shelf. On the opposite side of said ash-pit simple bearings *N'* are cast. Within the boxes *N* we place bearings *t* for the ends of grate-

bars *m*, shaped like one-half of an ordinary journal-bearing. These removable bearings we prefer to make of malleable iron or of some similar material that is easily worked, and we provide said removable bearings with transverse ribs *t'*, that enter corresponding depressions in the boxes *N* and preclude the accidental displacement of said bearings. One great advantage of providing a removable bearing *t* at one end, instead of supporting the grate-bar ends directly in the boxes *N'*, as heretofore practiced, lies in the fact that said boxes cannot be conveniently reached to fit them up and render them suitable to receive said grate-bars, and also in the fact that they may be so constructed that the grate-sections may be removed without disturbing the superimposed sections of the generator. When it is desired to remove a grate-bar, it is only necessary to raise the end supported by the bearing *t* and slide the said bearing inward (toward the center of the ash-pit) and downward, when the journal of the grate-bar may be lifted laterally over the rigid box *N* and then drawn longitudinally out of the solid bearing at the other end. When so operated, it is only necessary to have sufficient clear space between the bottom of the superimposed fire-pot section *C* and the removable journal-bearings *t* to allow the ribs *t'* to be lifted out of the depressions in the boxes *N*. The bottom of said fire-pot projects well inward over the journal ends of the grate-bars, as shown in Fig. 2, and thus serves to protect said journal ends, and also to prevent them from accidentally leaving the bearings *t'* when violently rocked.

On two opposite sides of the fire-pot or ash-pit rim (preferably the front and rear sides of the former) are fixed grate-sections *P*. (See one of said sections in Figs. 1 and 3.) These sections have one or more outwardly-projecting lugs *u*, that are bifurcated at their outer ends. On the lower side of the rim *B* are studs *v* with enlarged heads, said studs corresponding in number and position with the grate-lugs *u*. When a boiler is about to be assembled, the bifurcated lugs *u* at one end are slipped under the head of one of the studs *v* and caused to straddle the neck of said stud. The other bifurcated lugs are then swung into engagement with their respective studs, and

are locked in this position by a pin *w*, that is passed through the bifurcated lugs *u* outside of the studs, as best illustrated in Fig. 3 of the drawings.

- 5 The described improvements allow the several grate-sections and their connections to be made and finished cheaply and to be assembled more readily than in many of the furnaces and heaters now in use.
- 10 Having described our invention, we claim—
  1. An ash-pit formed with a series of integral inwardly-projecting boxes, having in combination therewith and seated therein a series of removable journal-bearings with
  - 15 transverse ribs *t*², that enter corresponding depressions in said boxes, as set forth, a series of grate-bars journaled in said removable

bearings, and a fire-pot section seated on said ash-pit, whose lower end projects inward over the journal ends of the said grate-bars, all substantially as and for the purpose specified.

2. A rim *B*, having one or more headed studs, as set forth, in combination with a fixed grate-section formed with bifurcated lateral projections adapted to engage said studs, and a key passed through said bifurcated projections to interlock said stud and grate, substantially as herein described.

ELISHA S. STAPLES.
ROUSE H. ARNOLD.
